TOOTH BAND

Charles Edward Boyd and Sidney Richardson,
Los Angeles, Calif.

Application February 15, 1933, Serial No. 656,872

5 Claims. (Cl. 32—14)

Our invention relates to a tooth band, particularly of the type utilized in the practice of orthodontia, and the principal objects of our invention are, to generally improve upon and simplify the construction of orthodontia tooth bands and to provide a band having relatively simple, practical and efficient means for detachably securing the ends of the band to each other and retaining the same in firm and substantial position upon the tooth to which the band is applied.

Further objects of our invention are to provide fastening and securing means for a tooth band that is devoid of parts that project to such a degree as to offer inconvenience to the patient as a result of contact of the tissues of the lips or tongue with the band attaching and securing means, and further, to provide a tooth band that may be easily and quickly applied to the tooth without involving time and labor on the part of the orthodontist in applying attaching means involving ligatures, screws, nuts and the like.

With the foregoing and other objects in view, our invention consists in certain novel features of construction and arrangements of parts that will be hereinafter more fully described and claimed and illustrated in the accompanying drawing in which:

Fig. 1 is a perspective view of a tooth band provided with our improved form of attaching and securing means.

Fig. 2 is an enlarged vertical section taken on the line 2—2 of Fig. 1.

Fig. 3 is a horizontal section taken on the line 3—3 of Fig. 1.

Fig. 4 is an elevational view partly in section of a modified form of the band securing means.

Fig. 5 is a cross section taken on the line 5—5 of Fig. 4.

Fig. 6 is an elevational view of a portion of a tooth band and showing a further modified form of the attaching means.

Fig. 7 is a vertical section taken on the line 7—7 of Fig. 6.

Fig. 8 is an elevational view of a portion of a tooth band and showing a further modified form of the attaching means.

Fig. 9 is a horizontal section taken on the line 9—9 of Fig. 8.

Fig. 10 is an elevational view of a portion of a tooth band and showing a further modified form of the attaching means.

Fig. 11 is a horizontal section taken on the line 11—11 of Fig. 10.

Referring by numerals to Figs. 1, 2 and 3 of the

accompanying drawing, which illustrate a preferred embodiment of our invention, 10 designates a tooth band of suitable metal such as gold, platinum or an alloy and which band is slightly curved in cross section so as to conform to the curvature of the tooth to which the band is applied. This band is split transversely, as designated by 11 and the length of the band is such that when it is properly applied to the tooth, the ends of the band will abut each other or occupy positions immediately adjacent to each other.

Secured on the outer face of the band adjacent to one end thereof, is a transversely disposed strap 12 and formed integral therewith and projecting toward and beyond the adjacent end of the band, is a narrow arm or finger 13, the lower edge of which is provided with a series of ratchet teeth 14.

The straps 12 and finger 13 may be formed integral with each other as illustrated in the drawing, or they may be separately formed and secured to each other and to the tooth band in any suitable manner, preferably by means of solder.

Secured to the outer face of the opposite end portion of the band are the end portions of a transversely disposed band 15, and formed therethrough is a horizontally disposed aperture 16 that is adapted to receive the end of finger 13 when the band is properly applied to the tooth. The engagement of the end of finger 13 in this aperture provides an interengaging connection at the ends of the band for maintaining the same in proper relation to each other and counteracting tendency of the ends of the band to twist or move vertically relative to each other.

Secured to the outer face of band 10, just beyond the band 15, is one end of a narrow strap or flat wire 17 and said strap passes through a horizontally disposed slot or opening 17a that is formed between strap 15 and the tooth band.

The free end of this strap 17 projects slightly beyond the end of the band to which said strap is secured and formed on the free end of said strap, is a tooth or hook 18, the point of which is adapted to engage in the notches between the teeth 14 of finger 13.

The narrow band or flat wire 17 is formed of resilient metal so that the end thereof that is provided with the hook or tooth 18, may flex downwardly to permit the point of the tooth 18 to ride over the teeth 14.

In applying our improved band, the same in open position is applied to the tooth and with a pair of pliers or suitable instrument that engages

the outer edges of the transverse bands 12 and 15, the ends of the band are formed toward each other, until the ends of said band abut each other or are positioned immediately adjacent to each other and during this operation, the tooth or point 18 on the resilient member 17, will ride past certain of the teeth 14 on strap 13 until the band is tightly set upon the tooth and the engagement of tooth 18 in one of the notches between the teeth 14, will effectually secure the ends of the band to each other so as to hold the same firmly anchored upon the tooth.

The engagement of the end of finger 13 in the slot or openings 17a holds the ends of the band in alignment with each other while being connected and while the tooth 18 is riding over the teeth 14.

While the band is being applied to the tooth as just described, the shoulders formed by the outer edges of the transverse bands 12 and 15 provide convenient bearings for the ends of the pliers or other instrument that is utilized in drawing the ends of the tooth band together.

All parts of the fastening means, including the straps 12 and 15 and the members 13 and 17, are formed of thin flat metal and as a result there are no undue or objectionable projections on the band to interfere with or offer inconvenience to the tongue and tissues of the lips of the patient.

To remove the band from the tooth, it is only necessary to apply a suitable tool or instrument to the member 17 and flex the same to such a degree as to effect a disengagement of the hook 18 from the teeth 14 and when such disengagement is effected, the ends of the band may be readily moved apart so as to enable the band to be quickly removed.

In the modified construction illustrated in Figs. 4 and 5, thin flat metal bands 19 and 20 are applied to the outer face of the tooth band 21 adjacent to its ends, so as to provide the necessary plier bearing shoulders and projecting from the intermediate portion of band 19, beyond the opposite end of the band, is a finger 22 provided on its upper and lower edges with small ratchet teeth 23. This finger is split longitudinally as designated by 24 in order that the portions above and below the split may be flexed toward each other.

Formed integral with the intermediate portion of band 20, is a lateral extension 25 and formed through said band and extension, is a horizontally disposed opening for the reception of the slotted finger 22 and the upper and lower faces of this slot are provided with ratchet teeth 26 that are adapted to be engaged by the teeth 23 or finger 22 when the ends of the band are drawn together. This arrangement provides a very strong and substantial connection between the ends of the band and to disconnect the ends of the band, a suitable tool is applied to the end of the slotted finger 22 and the portions above and below the slot are flexed toward each other a sufficient distance to permit the teeth 23 to ride past the teeth 26.

In this construction, the engagement of finger 22 in the opening through band 20 and extension 25, firmly holds the ends of the band against twisting or vertical movements relative to each other while the band is being applied to the tooth.

In the modified construction illustrated in Figs. 6 and 7, transversely disposed bands 27 and 28 of thin flat metal are applied to the outer face of the tooth band 29 adjacent to its ends and projecting from the intermediate portion of band 27, beyond the opposite end of the tooth band, is

a finger 30 that is provided on its lower edge with ratchet teeth 31.

Formed through the intermediate portion of band 27, is a horizontally disposed slot 32 that receives the finger 30 when the tooth band is positioned on the tooth and secured to the lower portion of band 28, is the lower end of a thin flat spring 33, the upper end of which is adapted to engage the ratchet teeth 31 when finger 30 is inserted through slot 32.

When this form of attaching means is disengaged, the point of a suitable tool is positioned behind the upper end of spring 33 and the same is forced outwardly so as to effect a disengagement of the end of said spring with the ratchet teeth on finger 30.

In the modified construction illustrated in Figs. 8 and 9, thin narrow metal bands 34 and 35 are applied to the outer face of the tooth band 36 adjacent to its ends and projecting from the intermediate portion of band 30 beyond the opposite end of the tooth band, is a narrow plate or finger 37 of resilient metal that is provided on its outer face with a series of ratchet teeth 38.

When the tooth band is positioned upon a tooth, finger 37 passes through a horizontally disposed slot or opening 39 that is formed in the intermediate portion of band 35 and formed on the outer edge of said band 35 is an inwardly projecting tooth 40 that is adapted to engage the teeth 38 on finger 37. The engagement of the finger 37 in the slot or opening 39 provides a substantial interengagement of parts to hold the ends of the tooth band in proper alignment and to resist relative twisting or vertical movements and to effect a disengagement of the connecting parts, it is only necessary to apply rearward pressure to the end of finger 37 so as to move said finger out of engagement with the restraining tooth 40.

In the modified construction illustrated in Figs. 10 and 11, short horizontally disposed tubular members 41 and 42 are secured on the outer face of the tooth band adjacent to its ends and tube 41 is internally threaded.

Mounted for rotation in tube 42, in the shank portion of a screw 43, the threaded portion of which is adapted to enter the internally threaded tube 41. The rear end of screw 43 is provided with a non-circular head 44 for the reception of a socket wrench and said screw is retained for rotation within tube 42 by a split ring or collar 45 that enters a groove 46 formed in said screw and which split ring or collar is positioned immediately adjacent to the inner end of tube 42.

In the various forms of our invention illustrated in Figs. 1 to 9 inclusive, we have shown the ends of the bands as abutting each other when properly applied to the tooth, but it will be understood that if desired the various parts of the connecting means may be applied to the band, which is of very thin metal so that when the band is applied to the tooth, its end portions will slide past each other and overlap as illustrated in Fig. 9.

Inasmuch as the bodies of the teeth to which the bands are applied bulge outwardly, the bands before being secured on the teeth, may be shaped so as to conform to the bulging contour of the teeth before being secured thereto and when the attaching means is properly secured, the bands, which are of thin metal, will snugly fit the contour of the teeth and this result cannot be attained where the bands are not split and are forced onto the bulging portions of the teeth.

Thus it will be seen that we have provided an orthodontic tooth and band having relatively simple and compact means for securely connecting the ends of the band when the same is applied to

5 the tooth and which fastening means is capable of being easily and quickly manipulated to secure the band on the tooth or to effect the removal of the band from the tooth.

An especially desirable feature of our improved tooth band fastening means in the absence of projecting parts that would otherwise tend to produce discomfort to the patient and a further advantage is the saving of time and labor on the part of the orthodontist in the manipulation of the band while the same is being applied to or removed from the tooth.

10 It will be understood that minor changes in the size, form and construction of the various parts of our improved tooth band may be made and substituted for those herein shown and described without departing from the spirit of the invention, 15 the scope of which is set forth in the appended claims.

We claim as our invention:

20 1. A tooth band, comprising a strip of metal adapted to encircle a tooth, a toothed member secured to one end of said band, a toothed member engaging hook secured to the other end of said band and shoulders on the outer face of 25 said metal strip adjacent its ends.

25 2. A tooth band, comprising a split metal band, a toothed member secured to said band adjacent

to one end thereof, a resilient toothed member engaging hook secured to the other end of said band and shoulders on the outer face of said band adjacent its ends.

3. The combination with a split tooth band, of a ratchet and detent connection carried by the ends of said band for holding the same in closed position and shoulders formed on the outer face of said band adjacent to said ratchet and detent connection.

10 4. A tooth band, comprising a split metal band transversely arranged strap secured on the outer face of said ring adjacent to its ends, a toothed finger secured to one end of said band on the outer face thereof, the strap on the opposite end 15 of the band being provided with an opening for the reception of said toothed finger and a resilient hook secured to the outer face of the other end of said band and adapted to engage the teeth of said ratchet finger.

20 5. A tooth band, comprising a split metal band, straps supplied to the outer face of said band adjacent to its ends, a toothed finger projecting from one of said straps, the other strap being provided with an aperture for the reception of 25 the end of said toothed finger and a detent mounted on said tooth band for engaging said toothed finger when the ends of the band are drawn together.
